UNITED STATES PATENT OFFICE.

SAMUEL WOOLSTON, OF VINCENTOWN, NEW JERSEY.

IMPROVEMENT IN MARINE CAMELS.

Specification forming part of Letters Patent No. 36,745, dated October 21, 1862.

To all whom it may concern:

Be it known that I, SAMUEL WOOLSTON, of Vincentown, in the county of Burlington and State of New Jersey, have invented a new and useful Improvement in Marine Camels; and I do hereby declare that the following is a full and exact description thereof, reference being had to the accompanying drawings, and to the letters of reference marked thereon.

In the accompanying drawings, Figure 1 represents a top view of my improvement in marine camels and the mode of applying the same to vessels. Fig. 2 represents a side view of the same.

The main portion of the camel A may be made in the simplest form with a flat bottom. It should be very large and well constructed. Upon one side of this camel is a series of arms, B, or platform, upon which the vessel is to rest when fastened to the camel. The body of the camel is divided into three longitudinal compartments by two partitions, E, Fig. 1; and the two outer of the compartments are again subdivided by transverse partitions G. The central is not thus subdivided. The compartments on the opposite sides of the camel communicate with each other by tubes or water-passages C, provided with stop-cocks I.

The operation is as follows: The outer compartments on that side of the camel next to the arms or platform B are filled with water by pumping or other suitable means, while the other compartments are left empty. This careens the camel, sinking the arms B deep in the water. Now, these arms B are brought under the vessel, and the latter is attached to the camel by chains of other suitable means. Then the stop-cocks I are opened in order to let the water flow through tubes C, Fig. 1, into the compartments on the opposite side of the camel. When the water has reached an equal height on both sides of the camel, or in both

of the outer compartments, the stop-cocks I are closed, and then the water may be pumped from the compartments next the vessel into those on the opposite side of the camel, thus leaving the middle compartment, and also the ones next the vessel, empty. These empty compartments buoy up the vessel, while the compartment filled with water counteracts the weight of the vessel, thus tending to right the camel and make it act like a lever, prying up the vessel. The force exerted upon the vessel is in proportion to the amount of water pumped into the opposite side of the camel, and can only be limited by the size of the camel and the quantity of water employed.

As the camel is very simple in its construction, it may be cheaply made of enormous size, if desired.

With this camel a vessel may be buoyed up and carried over a bar in a river with comparatively little labor.

The number of compartments and the general form of the camel may be varied without departing from my invention.

In raising sunken or grounded vessels two camels may be employed with appropriate tackle, the sides of the two camels being reversed.

Having thus fully described my invention, what I claim, and desire to secure by Letters Patent of the United States, is—

The above-described improvement in camels, the same being provided with separate water-compartments on the opposite sides, and arms, or a platform, B, constructed, arranged, and operated substantially as set forth, for the purposes specified.

SAMUEL WOOLSTON.
